THEODOR M. MUELLER, OF NEW YORK, N. Y.

HIGH-FREQUENCY MAGNETO.

958,754.

Specification of Letters Patent. Patented May 24, 1910.

Application filed August 4, 1908. Serial No. 446,923.

To all whom it may concern:

Be it known that I, THEODOR MARTIN MUELLER, a subject of the German Emperor, and a resident of the city of New York, 5 borough of Manhattan, in the county and State of New York, have invented a new and Improved High-Frequency Magneto, of which the following is a full, clear, and exact description.

10 My invention relates to magnetos, my purpose being to provide a machine having a wide range of adaptability as regards the frequency, and wave form of the current that may be generated, but the frequency is 15 dependent upon the speed of rotation of the machine.

More particularly stated, my invention comprehends a dynamo of the magneto type, in which the magnetic flux passes between 20 iron poles which are normally stationary, the magnetic flux being periodically interrupted by a slotted cylindrical-shaped inductor, having a considerable length extending through a number of separate parts of 25 iron.

My invention further contemplates a magneto-electric machine having a slotted cylindrical inductor member, pole pieces always stationary, and other pole pieces normally 30 stationary but adjustable at will and mating the pole pieces just mentioned, the slotted inductor being provided with iron members which periodically pass between the pole pieces which are always stationary and 35 those which are normally stationary but adjustable; so as to vary, break or reverse the flow of the magnetic flux passing through the various iron parts constituting its path.

My invention further contemplates means 40 whereby the adjustment of the stationary pole member, at the will of the operator, changes the character, or direction (as the case may be) of the flux as it passes through its lengthy path, thus materially changing 45 the character, of the currents generated.

My invention further comprises certain 50 improvements of a general character relative to magneto construction and conducive to compactness and general efficiency of the various parts of the machine.

Reference is to be had to the accompanying drawings forming a part of this specification, in which similar characters of reference indicate corresponding parts in all the 55 figures.

Figure 1 is a plan view of the magneto complete; Fig. 2 is a substantially central vertical section through the construction shown in Fig. 1 and exhibits the outer pole pieces, the inner pole-pieces or normally stationary but adjustable members disposed concentric to the outer pole pieces and made adjustable relatively to the same, and the slotted cylindrical inductor member which is as nearly as practicable disposed intermediate the outer pole pieces and the inner pole pieces and is free to revolve by aid of the pulley shown at the left. Fig. 3 is a substantially central vertical transverse section through the construction shown in Figs. 1 and 2, the section being taken through the inductor and midway of its length. Figs. 4 and 5 are diagrammatic sections, otherwise similar to Fig. 3, but showing the inner pole pieces or adjustable stationary members so adjusted that the distribution of the magnetic flux, while the machine is in action, is such as to cause the machine to operate as a generator of alternating currents having sine waves, these currents making four complete periods or cycles per revolution of the slotted cylindrical inductor member. Fig. 4^a shows a diagrammatic symbol representing an alternating current made by the machine when in the condition shown by Figs. 4 and 5; Figs. 6 and 7 indicate the action of the machine when the inner pole pieces are given a still further adjustment, so that the machine now generates alternating currents of four complete periods per revolution, the rise in potential, however, being much steeper at one moment than at another, so that the rise and fall of the potential are distorted, and the two half waves of one period are not alike; Fig. 7^a is a diagram representing the rise and fall of the potential of current generated by the machine under conditions represented by Figs. 6 and 7.

My invention is particularly designed for 100 the production of high frequency and high potential alternating currents, of various wave forms: also for the production of direct pulsating currents of high frequency and high potential.

Some of the various uses to which my invention are applied are,—for ignition purposes as applied to internal combustion engines, or by certain adjustments it may be employed as a direct current generator.

105

110

My invention proceeds, to some extent, upon the idea that in a generator of the magneto type, the currents generated may be varied considerably in their so-called 5 wave-forms, by adjusting certain pole pieces relatively to other pole pieces, so that both the direction and intensity of the lines of magnetic flux may be changed. The net result is that in my construction slight adjustment 10 of the inner stationary pole members enables the machines to generate currents differing widely from each other as regards their character or wave form. One adjustment produces alternating currents of 15 the sine wave form; and still another adjustment producing currents wherein the positive portion of the wave is different from the negative portion of the wave.

Mounted upon a base 28 is a metallic 20 framework 29 supporting magnetic poles 31, 33 which are secured to the ends of a permanent magnet 34 and lying in a horizontal plane; also poles 30, 32 of soft iron in which the magnetism is transient only, being periodically induced therein, as hereinafter described.

Disposed concentrically to the magnet 34 and partially encircling the same is a magnet 35, these two magnets constituting a 30 field of force in the poles 31, 33. Disposed intermediate the poles 30, 32 is an induction coil 37 provided with a core 36. This induction coil is of substantially cylindrical form and is therefore concentric with the 35 inner surfaces of the permanent magnets 34, 35. This renders the arrangement compact and also increases the inductance of the induction coil 37 owing to its close proximity to the mass of magnetic material contained 40 in the various magnets. Inside of the magnets 34, 35 is a space 38, and disposed within this space and supported upon the magnet 35 is a bracket or bar 40 provided with ends 39 for this purpose. A 45 spider 41 is provided with an annular bearing 42. Extending through the annular bearing 42 is a revoluble stem 43 whereby it may be turned. An inductor 45, having substantially a general cylindrical form, is 50 provided with slots 46 and with soft iron members 47, 48, 49, 50, these members being of substantially arcuate form in cross section, as will be understood from Fig. 3. Pole pieces 51, 52, of soft iron, and each having 55 the form of a segment, are connected together by a spacer 53 of brass or other non-magnetic material, these parts having the respective shapes indicated in Figs. 2 and 3. The spacer 53 is provided with a 60 neck 53^a which extends into the stem 43, the latter being fashioned to receive it and thus serving as a bearing for supporting the core and parts immediately connected with the same. An arm 54 is mounted rigidly 65 upon the spacer 53 and is used for turn-

ing the same slightly in order to adjust the spacer and its accompanying parts. A set screw 55 is revolubly mounted in the yoke 40 and is used to secure the spacer 53 against rotation. In order to adjust the spacer 53, 70 the set screw 55 is loosened and after the adjustment is made, the screw is tightened. The operator, by grasping the handle 54 and loosening the screw 55 may turn the spacer 53 into various positions, some of 75 which, for purposes elsewhere specified, are shown in the various figures.

The pole pieces 31, 33 being in close proximity to the ends of the permanent magnets are always of opposite polarity, one always 80 representing the North-seeking pole and the other representing the South-seeking pole of a permanent magnet. With regard to the pole pieces 30, 32, however, the situation is different. These pole pieces, together with 85 the core 36, are of soft iron. Hence the pole pieces 30, 32 have no permanent polarity. If either of the latter happens to be so situated that the magnetic lines can flow through it in such direction as to make it, 90 for the moment, a North-seeking pole, it becomes such. If, for the moment, it happens to be so situated that the lines of force tend to make it a South-seeking pole, it becomes the same. Hence, the magnetism in the pole 95 pieces 30, 32 is transient and reversible in direction, whereas that of the pole pieces 31, 33 remains constant and unchanged. Bearing this explanation in mind, it will readily be seen that a lengthy magnetic circuit 100 through the permanent magnets and through the pole pieces 31, 33 of these magnets, may be completed in either of two directions through the pole pieces 30, 32 and the core 36, connecting them together, the direction 105 of the line of force through the pole pieces 30, 32 being dependent upon the relative positions of the inductors 47, 48, 49, 50. It will also be seen that by turning the inductor 110 the constantly shifting position of the several iron members 47, 48, 49, 50 may open and close the magnetic circuit through the permanent magnets and may also change the direction of flow of the magnetic lines 115 relatively to the pole pieces 51, 52 and the spacer 53, it being understood that these parts are included in the magnetic circuit. This much being admitted, it will be seen that the winding of wire upon the core 36 will have set up in it momentary currents, 120 the character of which will vary with motions of the inductor.

The operation of my device is as follows and may be more readily understood by reference to Figs. 4 to 7 inclusive: In order to 125 adjust the machine for the generation of alternating currents, the arm 54 is turned so that the inner pole pieces 51, 52 occupy the positions indicated in Figs. 4 and 5; that is to say, the central line through the pole 130

pieces 51, 52 and spacer 53 is vertical. The spacer 53 is now locked by aid of the set screw 55, as will be understood from Fig. 2. Power now being applied to the pulley 44, 5 the inductor, and nothing else, is turned. Suppose that at the start the inductor happens to occupy the position indicated in Fig. 4. Suppose, further, (for convenience) that the flow of the magnetic lines is from the 10 pole piece 33 and toward the pole piece 31, of the permanent magnets 34 and 35. The intervening path being made up principally of soft iron, the parts will enable the lines of force to cross from the one permanent 15 magnet pole to the other, the direction of the magnetic lines, however, being greatly distorted. The complete magnetic circuit is as follows: pole piece 33, iron member 50, pole piece 52, iron member 49, pole piece 32, core 20 36 (see Figs. 2 and 4), pole piece 30, iron member 47, pole piece 51, iron member 48, pole piece 31 to permanent magnets 34, 35, thence back to pole piece 33. This causes in the winding upon the core 36 a momentary current having one direction. The 25 turning of the inductor soon moves the iron members 47, 48, 49, 50 a little farther, as indicated in Fig. 5, and now the magnetic circuit may be traced as follows: pole piece 33, iron member 50, pole piece 51, iron member 47, pole piece 30, core 36, pole piece 32, iron member 49, pole piece 52, iron member 48, pole piece 31, to permanent magnets 34, 35, thence through these to pole piece 33. 30 As may be seen by contrasting the arrows in Figs. 4 and 5, the direction of travel of the lines of force through the pole pieces 30, 32 is in Fig. 5 reversed relatively to their direction of travel in Fig. 4. The rotary 35 movement of the inductor being continued, the lines of force again change direction through all of the pole pieces except those numbered 31, 33, the result being a current similar to that formed when the parts are in 40 the position indicated in Fig. 4. A further movement of the inductor causes the parts to assume the position indicated in Fig. 5, the result being another reversal of the current generated. Similar reversals are made 45 by the further movements of the inductor. In this instance the running of the machine causes the generation of four currents in each direction for each revolution of the inductor; that is to say, the machine gives with 50 this adjustment four complete periods per revolution. Suppose, now, that we wish the machine to generate an alternating current having considerable distortion of the wave 55 form of the potential and current. This I accomplish by a further adjustment of the arm 54. This arm is turned until the pole pieces 51, 52 and the spacer 53 assume the respective positions indicated for these parts in Figs. 6 and 7. The position is attained 60 when the central line through the pole pieces 51, 52 and the spacer 53 is oblique 22 $\frac{1}{2}$ degrees from the vertical; in other words, the center line through the pole pieces 51, 52 and spacer 53 is inclined in a contraclockwise direction to the extent indicated in Figs. 6 70 and 7. The inductor being now turned in a clockwise direction, the lines of force alternate in direction through the pole pieces 30, 32, the result being an alternating current of the general type indicated in Fig. 7^a, the potential and amperage of this current being 75 distorted, as will be understood from the curve represented by the figure last mentioned, in which it will be observed that the curve does not represent a true sine curve, 80 but is one in which the lines representing the curve are unequally inclined to the horizontal, as will be readily observed. 85 It will be seen that the machine may be employed for quite a diversity of uses. The character of the wave form may be varied by simply changing the position of the inner stationary pole pieces 51 and 52 so that an 90 alternating current may be produced as may be desired. 95 While in the particular type of machine above described I show the inductor as revolvable and the pole pieces inside and outside of the inductor as stationary while the machine is in action, I do not limit myself to this exact construction, as mechanical reversals and equivalents may be employed by persons skilled in the art, and the scope of my invention is not limited to the precise 100 construction shown in the drawings. 105 Having thus described my invention, I claim as new and desire to secure by Letters Patent:

1. The combination of a permanent magnet provided with poles, a magnetic member, provided with poles and spaced apart from said permanent magnet, an inductor having a portion adapted to pass successively all of said poles, and a core disposed intermediate said magnet poles and also intermediate said poles of magnetic material. 110
2. The combination of a permanent magnet provided with poles, a sector-shaped pole piece normally stationary in relation to said magnet, means for angularly adjusting said pole piece relatively to said magnet, a magnetizable circuit provided with a winding, and an inductor element movable relatively to said magnet and to said pole piece for the purpose of affecting lines of force extending from said magnet to said pole piece and said circuit, whereby a current will be induced in said winding, substantially as described. 115
3. The combination of a permanent magnet provided with poles of opposite polarity, 120 members of magnetic material adapted to be energized in opposite sense by induction from said magnet poles, a revolvable inductor provided with members of magnetic material movable relatively to said magnet poles and 125
4. The combination of a permanent magnet provided with poles, a magnetic member, provided with poles and spaced apart from said permanent magnet, an inductor having a portion adapted to pass successively all of said poles, and a core disposed intermediate said magnet poles and also intermediate said poles of magnetic material. 130

also to said members of magnetic material, a member having portions of soft iron mounted within said revoluble inductor, and means controllable at will for partially turning said member having portions of soft iron within said inductor for the purpose of effecting the distribution of the magnetic field from said magnet through said inductor.

4. The combination of a magnet, a revoluble inductor of substantially cylindrical form provided with members of magnetic material to be acted upon by said magnet, and a stationary member mounted within said revoluble inductor, said stationary member comprising a plurality of members of magnetic material separated from each other by a non-magnetic substance, and means including a magnetizable circuit, operatively located with relation to the stationary member, a coil thereon, whereby a current may be induced in said coil, substantially as described.

5. The combination of a magnet provided with poles, a revoluble member affected by the magnetic lines of force from said poles for the purpose of generating electric currents, and a member concentric to said revoluble member and adjustable in relation to said permanent magnet, a magnetic circuit having its poles spaced from the poles of said magnet, a coil thereon, whereby alternating currents may be generated, substantially as described.

6. The combination of a magnet provided with poles, a revoluble inductor member disposed adjacent to said poles for the purpose of generating electric currents, and comprising four iron members spaced apart, a plurality of normally stationary pole pieces, means for adjusting the same, a magnetic circuit arranged in quadrature to the poles of said magnet, a coil thereon, whereby when the inductor member is rotated an alternating current having four periods per revolution will be induced in said coil, substantially as described.

7. The combination of a plurality of permanent magnets, each of substantially horse-shoe form and provided with poles, a hollow, revoluble inductor member disposed adjacent to said poles and concentric to the same, a plurality of pole pieces mounted within said inductor, and a spacer of non-magnetic material disposed intermediate said pole pieces, and means, including a laminated magnetic circuit provided with a coil thereon for receiving the flux from said magnets, as modified by said inductor, whereby a current may be induced in said coil substantially as described.

8. The combination of a plurality of permanent magnets, each of substantially horse-shoe form and provided with poles, a revoluble inductor disposed adjacent to said poles and concentric to the same, a plurality of

pole-pieces mounted within said inductor, a spacer of non-magnetic material disposed intermediate said pole-pieces, and means for adjusting said pole-pieces relatively to said magnets, a magnetizable circuit having its poles arranged in inductive relation to said inductor and pole-pieces, a coil thereon, whereby an alternating current may be induced in said coil, and whereby the wave form of said currents may be varied, substantially as described.

9. The combination of a permanent magnet provided with poles, a revoluble member disposed adjacent to said poles and affected by the lines of force therefrom for the purpose of generating electric currents, and mechanism, including a member of soft iron, disposed adjacent to said magnets for the purpose of changing the direction of the magnetic lines from said magnets and through said revoluble member, a magnetizable circuit and a coil thereon, disposed in inductive relation to said magnet, substantially as described.

10. The combination of a permanent magnet provided with poles, magnetizable members provided with poles, an induction coil on the members, said poles of said members being disposed intermediate the poles of said permanent magnet, and a slotted revoluble inductor disposed adjacent to all of said poles for the purpose of generating electric currents, and a magnetic member for directing the flux from the permanent magnet to the core of the induction coil, substantially as described.

11. The combination with permanent magnets, a soft iron member arranged in quadrature to the permanent magnets, an induction coil, the core of which is included in the magnetic circuit of said soft iron members, sector-shaped members arranged within the poles of the permanent magnets and said members, and a cylindrical shaped inductor member adapted for rotation and disposed between said poles and the sector-shaped members, substantially as described.

12. The combination with permanent magnets, a soft iron member arranged in quadrature to the permanent magnets, an induction coil, the core of which is included in the magnetic circuit of the said soft iron members, sector-shaped members arranged within the poles of the permanent magnets and said members, and a cylindrical shaped inductor member adapted for rotation and disposed between said poles and the sector-shaped members, and means for adjusting the sector-shaped members, substantially as described.

13. The combination with permanent magnets, a soft iron member arranged in quadrature to the permanent magnets, an induction coil, the core of which is included in the magnetic circuit of said soft iron

members, sector-shaped members arranged within the poles of the permanent magnets and said members, and a slotted cylindrical-shaped inductor member adapted for rotation and disposed between said poles and the members, substantially as described.

5 In testimony whereof I have signed my

name to this specification in the presence of two subscribing witnesses.
